(57) **CLAIM**

The ornamental design for a spearhead, as shown and described.

DESCRIPTION

FIG. 1 is a perspective view of a spearhead showing our new design;

FIG. 2 is another perspective view of the spearhead shown in FIG. 1;

FIG. 3 is a front elevational view of the spearhead shown in FIG. 1, the rear view being identical thereto;

FIG. 4 is a right side elevational view of the spearhead shown in FIG. 1, the left side view being identical thereto;

FIG. 5 is a top plan view of the spearhead shown in FIG. 1; and,

FIG. 6 is a bottom plan view of the spearhead shown in FIG. 1.

The phantom, broken lines shown in the drawings form part of the design that is not claimed herein.
